His Attorney.

UNITED STATES PATENT OFFICE

WILLEM F. WESTENDORP, OF SCHENECTADY, NEW YORK, ASSIGNOR TO GENERAL ELECTRIC COMPANY, A CORPORATION OF NEW YORK

ELECTRIC ILLUMINATING APPARATUS

Application filed December 17, 1932. Serial No. 647,769.

My invention relates to electric illuminating apparatus. More particularly it relates to electric discharge illuminating apparatus operable from a source of single phase alternating current. One object of my invention is the provision of improved illuminating apparatus of this character which will operate on a single phase circuit without producing visible flicker. Another object of my invention is the provision of improved apparatus of this character the illumination from which may be made to resemble that from some other source. This application is a continuation-in-part of my copending application Serial No. 547,156, filed June 26, 1931, for Electric illuminating apparatus.

My invention will be better understood from the following description taken in connection with the accompanying drawing, and its scope will be pointed out in the appended claims.

In the single figure of the drawing which illustrates an embodiment of my invention I have shown at 1 and 2 two similar positive column discharge lamps each of which comprises a suitable envelope of glass or quartz containing a gas or vapor or a suitable gaseous mixture which becomes luminous when subjected to an electric discharge. Various gases and vapors may be used for this purpose depending largely upon the particular kind of light which it is desired that the lamp shall produce; for example, the gas or vapor may be argon, neon, helium, krypton, xenon, mercury or sodium. Lamp 1 has the hot cathode 3 and main anode 4. Similarly, lamp 2 has a hot cathode 5 and main anode 6. For starting purposes both lamps are provided with a series of auxiliary electrodes 7 which connect with the main anodes of the respective lamps through resistances 8 whose value may, for example, be 2000 ohms, 1000 ohms, 500 ohms and 250 ohms, counting from the cathode to the main anode. The hot cathodes 3 and 5 are shown directly connected respectively with the two sides 9 and 10 of the alternating current supply circuit which, for example, may be at 110 volts or 220 volts and have a frequency of 60 cycles. Each cathode is provided with a

heater, one end of which is connected with the cathode and the other end connected with the opposite side of the supply circuit whereby each heater connects directly across the supply circuit. The main anodes 4 and 6 connect through the reactor 12, now to be described, with the sides 10 and 9 respectively of the alternating current supply which is controlled by switch 11.

Reactor 12 comprises the core 13 upon which is wound a bifilar winding comprising the two coils 14 and 15, coil 14 being arranged in series with the main anode 4 and coil 15 being arranged in series with the main anode 6. In circuit with the respective coils 14 and 15 are the controlling resistances 16 and 17. The two coils 14 and 15 comprising the bifilar winding of reactor 12 are connected in the circuit in such a manner that the core is magnetized in the same sense by the rectified currents passing through each of the lamps. As the flux linkages tend to remain constant the sum of the absolute value of the currents through the two coils will tend to remain constant the result of which is that currents of approximately rectangular wave shape pass through the lamps with no interval between the successive waves, which currents have a 180° phase displacement relative to each other; the total light output from the two lamps being constant neglecting a slight ripple.

When the above described apparatus is thrown on the alternating current supply circuit as by closing switch 11, the cathodes of the two lamps are heated and by reason of the ionizing effect of the auxiliary anodes the discharge quickly travels up each lamp to the main anode thereof every cycle although on different half cycles for the two lamps. Since the resistances in series with the auxiliary anodes are large a very small current only passes to each during the operation of the lamp. As each lamp rectifies the current taken by it and as the lamps are connected to the supply circuit reversely, the current flows in the same direction in the two coils 14 and 15.

Instead of employing a reactor having a bifilar winding I may in certain cases em-

ploy a reactor having a winding comprising two separated coils on an open core in which case there is sufficient coupling between the coils to cause an overlapping of the light impulses from the two lamps. Because of the leakage reactance, the wave shape is more triangular and less rectangular in form, the base portions of the triangles overlapping. With such a construction the light never reduces to a zero value but the ripple is larger than where a reactor having a bifilar winding is used.

Each of the two lamps 1 and 2 may contain various gases or vapors such as those mentioned above depending upon the character of light desired. For the purpose of producing illumination which resembles that from some known source or gives the sensation thereof I employ gases or vapors in the respective lamps such that the combined light from the two lamps will have the desired character. For producing the sensation of daylight I may, for example, use neon in one lamp and mercury vapor in the other, the two lamps taken together as a unit thereby providing a combination of red and green rays which give to a person the sensation which is substantially the same as that produced by daylight.

I have chosen the particular embodiment described above as illustrative of my invention and it will be apparent that various other modifications may be made without departing from the spirit and scope of my invention which modifications I aim to cover by the appended claims:

What I claim as new and desire to secure by Letters Patent of the United States is:

1. Electric discharge apparatus for producing illumination without visible flicker from a single phase alternating current supply circuit comprising a plurality of rectifying discharge lamps, means connecting said lamps to said circuit in parallel and in a relatively reverse manner, and a reactor in the connecting means having windings arranged to produce fluxes in the same sense.

2. Electric discharge apparatus for producing illumination without visible flicker from a single phase alternating current supply comprising a plurality of discharge lamps connected in parallel across said supply to operate respectively on the positive and negative half waves thereof, and a reactor having inductively related windings each in the connection of one of said lamps and arranged to produce fluxes in the same sense.

3. Electric discharge apparatus for producing illumination without visible flicker from a single phase alternating current supply comprising a plurality of discharge lamps each having a cathode and an anode, means connecting the cathode of one lamp and the anode of the other lamp to one side

of the supply, means for connecting the other cathode and anode to the other side of the supply, and a reactor having a plurality of windings in the connections of the respective lamps, said windings being arranged to produce fluxes in the same sense. 70

4. Electric discharge apparatus for producing illumination without visible flicker from a single phase alternating current supply comprising a plurality of discharge lamps connected in parallel across said supply to operate respectively on the positive and negative half waves thereof and a reactor comprising a core having a plurality of windings thereon connected in series with the respective lamps and arranged to magnetize the core in the same sense. 75

5. Electric discharge apparatus for producing illumination without visible flicker from a single phase alternating current supply comprising a plurality of discharge lamps connected in parallel across said supply to operate respectively on the positive and negative half waves thereof and a reactor having bifilar windings each in series with one of said lamps and arranged to produce fluxes in the same sense. 80

6. Electric discharge apparatus for producing illumination without visible flicker from a single phase alternating current supply comprising a plurality of discharge lamps each having a cathode and an anode, means for connecting the cathode of one lamp and the anode of the other lamp to one side of the supply, means for connecting the other cathode and anode to the other side of the supply, and a reactor comprising a core having bifilar windings thereon, said windings being in series with the respective anodes and connected to magnetize the core in the same sense. 90

7. Electric discharge apparatus for producing illumination without visible flicker from an alternating current supply circuit, comprising a plurality of rectifying discharge lamps each having a cathode, a main anode and a starting anode, said lamps being reversely connected with said circuit in parallel, and a reactor in the connection of said lamps with the circuit having a plurality of windings arranged to produce fluxes in the same sense. 100

8. Electric discharge apparatus for producing illumination without visible flicker from a single phase alternating current supply circuit, comprising a plurality of rectifying discharge lamps reversely connected with the circuit in parallel, a bifilar reactor and limiting resistances said reactor and resistances being arranged in the connections of said lamps with the circuit and both windings of the reactor being arranged to magnetize the core of the reactor in the same sense. 110

9. Electric discharge apparatus for producing illumination without visible flicker 120

from a single phase alternating current supply circuit, comprising a plurality of rectifying discharge lamps each having a hot cathode, a main anode and an auxiliary starting anode, said lamps being connected in parallel across said circuit and the respective cathodes being connected with the opposite sides of the circuit, a reactor having a plurality of inductively related windings on the same core connected in circuit with the main anodes of the lamps and arranged to magnetize the core in the same direction, and a limiting resistance in each anode circuit.

10. Electric discharge apparatus for producing illumination without visible flicker from a single phase alternating current supply circuit comprising a plurality of rectifying discharge lamps, means connecting said lamps to said circuit in parallel in a relatively reverse manner, and a reactor in the connecting means having windings arranged to produce fluxes in the same sense, one of said lamps containing neon and another containing mercury vapor whereby the combined light resembles daylight.

15. Electric discharge apparatus for producing illumination which resembles daylight and without visible flicker from a single phase alternating current supply circuit, comprising a plurality of rectifying discharge lamps reversely connected with the circuit in parallel, a bifilar reactor and limiting resistances said reactor and resistances being arranged in the connections of said lamps with the circuit and both windings of the reactor being arranged to magnetize the core of the reactor in the same sense, one of said lamps containing neon and the other containing mercury vapor.

20 40 In witness whereof, I have hereunto set my hand.

WILLEM F. WESTENDORP.
